Filed Aug. 5, 1966, Ser. No. 3,371

Term of patent 14 years

(Cl. D74—1)

FIG. 1 is a top plan view of a novelty scratch pad embodying the design of the present invention;

FIG. 2 is a corresponding left side elevation;

FIG. 3 is a corresponding right side elevation;

FIG. 4 is a top edge view; and

FIG. 5 is a bottom edge view thereof.

The back face of the scratch pad shown is essentially plain.

The essential features of the design reside in the portions shown in solid lines, particularly the round base and elevated tip portion which characterize the novelty member attached to the scratch pad. Conventional printed matter being shown in broken lines in FIG. 1.

We claim:

The ornamental design for a novelty scratch pad, as shown and described.
